LESTER F. BIRD, OF NEWARK, NEW JERSEY, ASSIGNOR TO HANOVIA CHEMICAL AND MANUFACTURING COMPANY, OF NEWARK, NEW JERSEY, A CORPORATION OF NEW JERSEY

HOOD FOR THERAPEUTIC LAMPS

Application filed July 26, 1930. Serial No. 470,950.

This invention refers to hoods and reflectors for therapeutic lamps of any character and especially to those known as mercury arc lamps.

5 There are certain features in connection with the use of mercury arc lamps that make this invention of peculiar value. The use of mercury arc lamps is increasing steadily since they are a very efficient source of 10 ultraviolet light and are active in that region of the spectrum that has been shown to be effective in the production of sunburn.

It is highly desirable that patients who are exposed to the rays from these lamps 15 be given the maximum amount of light without producing local burns. Such burns may result from variations in intensity on the surface of the body.

The increasing use of these lamps in equipment known as solariums or sun rooms increases the need for high power lamps of uniform light distribution since such a light source results in the maximum irradiation in the shortest possible time.

25 The light given out from an open burner without the use of a modifier or reflector is not suitable for the maximum results because of its distribution. The open burner acts substantially as a point source of light 30 and so is more intense close to the burner than farther away.

Because of the speed of treatment that is desired the patients are placed as close to the lamp as the distribution of the light 35 will permit. If the patient is far away from the open lamp he will receive practically uniform illumination but at the distances ordinarily employed for this purpose, this is not the case.

40 The usual treatment method is to place the patient in a prone position beneath the burner at a distance of 4 to 6 feet. With this distance from the burner for treatments, the light falling on the part of the 45 patient directly beneath the burner is very much more intense than that on the extremities, in fact it may easily amount to twice the intensity of that on the extremities. Such conditions as these make some form 50 of modifier or reflector a necessity if the

maximum results are secured from the lamp.

The object of this invention is to provide a modifier by means of which substantially uniform illumination is obtained below the burner in the place normally occupied by 55 the patient, thus enabling the maximum benefit from a lamp. The efficiency of the light source is also greatly increased since almost all of the light from the burner is converted into useful light.

60 Light is returned from all directions and is directed downward so that it becomes useful for the patient. The reflecting surfaces are composed of polished surfaces of those metals such as chromium and aluminum 65 which have been found to be the most efficient in the reflection of ultraviolet light.

A further object is the provision of a modifier for the light so that the light in those 70 places about the lamp that normally receive weakened radiation are strengthened, and those that would be too strong are weakened. The reflector provides a strong light field for the patients head and feet but does not appreciably affect the mid section.

75 The mercury arc burner which produces the light is usually a quartz tube about $\frac{3}{4}$ inch in diameter and 5 inches long. This envelope contains only mercury and mercury vapor. Under the proper conditions the 80 burner may be connected to a power source of electricity and an arc established within the quartz tube.

85 The arc in the burner fills the quartz container from one end to the other and so is in itself a distributed source of light. This physical shape of the light source requires a reflector differing radically from those ordinarily employed with concentrated filament lamps.

90 My invention takes this condition into account and the reflector is so designed that the greatest possible use is made of the distribution of the light source.

95 These and other advantageous objects, which will later appear, are accomplished by the simple and practical construction and arrangement of parts hereinafter described and exhibited in the accompanying drawings, forming part hereof, and in which:

Figure 1 represents an end view of the device, with a portion of an end plate removed.

Figure 2 represents a view taken on line 5 2-2 of Figure 1.

Figure 3 represents a diagram illustrating the intensities of light necessary to produce uniform illumination of a flat surface.

Referring to the drawings, the reflecting 10 hood is shown to include a plurality of metal plates 4, of varying sizes, each plate having lateral flanges 4' and end flanges 6. The plates are made from metals, such as chromium and aluminum, which may be highly 15 polished so that the interior faces of the plates may have high reflecting powers for ultraviolet radiations.

End plates 5 are attached to the reflecting plates 4 by means of bolts 7 passing 20 through the flanges 6. The end plates 5 are provided with flanges 5'. Immediately behind the light source 9, a reflecting plate is omitted to provide a space 8 for ventilating purposes. The space 8 is one inch in 25 length. The plates 4 are arcuately arranged and both sides of the hood are symmetrical, the plates on one side of the hood being inclined successively to the flange 5-5 at angles of $49\frac{1}{2}^\circ$, 44° , $25\frac{1}{4}^\circ$, and 7° , said 30 plates having respectively widths of $1\frac{25}{32}$ inches, $3\frac{9}{32}$ inches, $1\frac{57}{64}$ inches and $2\frac{3}{32}$ inch, the plates on both sides of the hood being arranged in identically the same manner.

According to the well known laws of 35 light distribution the energy falling on a given perpendicular surface varies with the distance of the light source from the surface. That is, if a surface is one foot from a given light source it will have a larger 40 amount of light energy falling upon it than it will at a distance of two feet or more from the lamp. The energy, if from a point source, will vary approximately inversely as 45 the square of the distance. If the distance is increased the light energy is reduced. If the distance is decreased, the light energy is increased.

Where uniform light intensity is desired 50 upon a given surface, as is the case when a patient is receiving a treatment from a lamp, since the patient represents a relatively flat straight surface, considerable modification of the light distribution is 55 necessary to obtain uniform intensity.

With the unmodified burner and a patient 60 four feet directly under the lamp the distance from the burner is considerably greater from the patient's head and feet than from mid-section. Such distribution results 65 in a considerable increase in the light received by the mid-section as compared to that secured by the head and feet.

The distribution of the light from an unmodified light source such as the mercury

arc is practically uniform around the burner. When the burner is mounted four feet above a patient who is six feet long the mid-section of the patient is four feet from the burner while his head and feet are all 70 of five feet away from the lamp.

As stated before, the light at his head and feet will be considerably weaker than at the mid-section and this will be approximately inversely as the square of the distance. 75 Since one distance is four and the other distance five, the corresponding intensities will be approximately as sixteen is to twenty-five, that is, the light at the patient's feet and head will be only $16/25$ th as strong as that at the mid-section.

There is still another condition that results in the weakening of the light at the patient's head and feet over the light at the mid-section and that is the angle at which the light strikes the surface. The smaller the angle at which the light strikes the surface, the lower the intensity per unit area on the surface. For example, a surface of ten square inches in a plane surface, at right 90 angles to the light, would receive the maximum light.

If it were edge on to the light there would be no light striking the surface, and for an intermediate angle there would be less light 95 striking the surface than would be the case when it is at right angles to the light. Under the conditions given previously with the arc four feet above the patient and the patient six feet long, the angle at which the light hits the patient's head and feet is such that the intensity per unit area is reduced to about four-fifths of the intensity 100 that would be secured by a surface at right angles to the light at the same location.

In the design of the modifier both the angle of incidence of the light and the distance from the light source must be taken into account.

Starting with the mid-section of the patient and proceeding toward the head the light distribution should follow a regularly increasing curve as illustrated in Figure 3.

The reflector adds greatly to the efficiency 110 of the light source because it redirects light that normally would be wasted so that it is available on the patient. No reflector is 100 per cent efficient as a reflector and does not reflect all of the light it receives. Some of the light is absorbed and some is scattered 120 so that it is lost.

Reflectors are available however that will reflect in a useful direction about 50 percent of the incident light. The increase in intensity that is possible with a reflector of 125 the proper design is a matter of common knowledge. Ordinary designs of reflectors are not suitable for the purpose for which this invention was made.

The reasons for this are apparent when 130

the source of the light and the desired distribution are considered. The light source is not a concentrated filament as is common in incandescent lamps but is a cylindrical tube about five inches in length. The light intensity throughout the length of the tube is about constant so that the light source is distributed itself.

This fact influences the design of the reflector. It is common practice with reflectors to design them so that the light is brought to a focus giving a very concentrated spot of high intensity. Such distribution is not desirable for a therapeutic lamp which is used for irradiation of a patient.

Such distribution would result very unfavorably since the patient might receive too much light in one place and very much less in another. The light striking the patient should be of uniform strength throughout.

Another very important advantage is secured from the invention because of the peculiar and inherent characteristics of a quartz mercury arc lamp. These arcs are affected markedly by the temperature of the surrounding envelope and the temperature of the envelope is in turn affected by many external conditions such as ventilation, air temperature and radiation. The air temperature in the room where the lamps are located while of importance to the burner is however not within the control of the burner and hood designer.

The temperature of the air immediately surrounding the burner, the ventilation of the hood, the radiation of heat from the burner and the distribution of the light from the burner are all more or less under the control of the designer.

Hoods and reflectors that are improperly designed cause high temperatures to exist in the air around the burner. This does not damage the burner but does reduce the efficiency and the light output from it. The input power to the burner is affected and reduced by a rise in temperature of the burner envelope and this in turn causes a reduction in the output from the lamp.

Proper ventilation of the hood is of considerable importance in securing the maximum output from a given burner. There can easily exist a loss in output from a burner of 30 percent by placing the burner in a location having poor ventilation.

Another important consideration in the hood design is that of properly directing the radiation given off from the burner. Improperly designed hoods reflect the radiations directly back into the burner and so add to its temperature. This of course results in reduced light output and is undesirable.

The quartz mercury arc is quite opaque to the radiations that it emits so there is

no gain in intensity by trying to reflect light through the burner itself. It is advantageous that a reflector does not reflect any radiations toward the burner.

The invention successfully cares for all of these important considerations. A maximum of ventilation is provided for the burner and the natural draft associated with the burner provides a continuous flow of cool air to the burner at all times. The hood for this reason does not interfere in any way with the burner temperature and so provides for the coolest possible operating conditions.

The surfaces of the reflector, while intended for excellent distribution of light to the patient who might be enjoying the radiations from the lamp, are arranged so that there is no reflected radiation striking the burner. This is a great advantage since the burner is kept cooler and at a higher efficiency.

Having thus described the invention, what I claim as new and desire to secure by Letters Patent, is:

In combination with a therapeutic mercury vapor arc lamp, a reflecting hood comprising a pair of end plates, and a plurality of plane reflecting surfaces attached to the end plates, and arcuately arranged, the plates on one side of the hood being inclined successively to the longitudinal free edge of the hood at angles of $49\frac{1}{2}^\circ$, $44^\circ 25\frac{1}{4}^\circ$, and 7° , and said plates having respectively widths of $1\frac{25}{32}$ inches, $3\frac{9}{32}$ inches, $1\frac{57}{64}$ inches and $2\frac{3}{32}$ inch, the plates on the other side of the hood being arranged in identically the same manner, the adjacent plates of each side being spaced apart, a distance of one inch, the light source being positioned on a line through the center of the hood at a distance of $2\frac{1}{8}$ inches from the longitudinal free edge.

This specification signed this 21st day of July, 1930.
